Attorney

UNITED STATES PATENT OFFICE.

CHARLES R. MILLER, OF COLLINSVILLE, TEXAS.

GREASE-GUN.

1,285,776.

Specification of Letters Patent. Patented Nov. 26, 1918.

Application filed August 27, 1918. Serial No. 251,681.

To all whom it may concern:

Be it known that I, CHARLES R. MILLER, a citizen of the United States of America, residing at Collinsville, in the county of 5 Grayson and State of Texas, have invented certain new and useful Improvements in Grease-Guns, of which the following is a specification.

My invention relates to devices for handling grease for various kinds of machinery and more particularly to grease guns; and the object is to provide a simple device which can be easily filled with grease and by which the grease can be readily applied wherever 15 required. One object is to provide a telescopic filler by which the grease may be taken into the grease gun without getting the grease on the hands, and which makes the filling easily and quickly done. 20 Other objects and advantages will be fully explained in the following description and the invention will be more particularly pointed out in the claims.

Reference is had to the accompanying 25 drawings which form a part of this application.

Figure 1 is a side elevation of the grease gun. Fig. 2 is a side elevation, this view showing the gun turned one quarter around. 30 Fig. 3 is a broken sectional view, showing details of construction and showing the parts enlarged. Fig. 4 illustrates the position of the filler in the act of taking in a charge of grease, parts of the operating 35 mechanism being omitted. Fig. 5 is an end view of the telescopic filler.

Similar characters of reference are used to indicate the same parts throughout the several views.

40 The gun includes a barrel 1 which is closed at the intake end by a cap 2 which is hingedly connected thereto, the hinge members including a shank 3 and jaw members 4 secured to the outside of the barrel and pivot bolt. A spring clamp 5 is provided for holding the cap 2 open during a filling operation. When the cap is pushed open to the position shown by dotted outline in Fig. 1 the shank 3 will be caught by the 45 spring clamping members 5. The other end of the barrel 1 is closed by a plug 6 which serves as a guide for the plunger rod 7 and for other purposes hereinafter explained. A telescopic filler tube 8 is mounted in the 50 barrel 1 and is movable therein by the plun-

ger 9 and its rod 7 which is provided with lugs 10 for this purpose.

The cap 2 has internal threads and the filler or intake end of the tube 8 is provided with threads for engaging the cap for locking the cap closed. The cap 2 is provided with a packing gasket 11 against which the filler tube presses. The filler 8 is provided with a perforated plug 12 by which the filler tube 8 is actuated. The plunger 9 operates 65 within the tube 8 for discharging grease as hereinafter explained. The plug 12 has a slot 13 which is enlarged in the central part for the operation of the plunger rod 7. The slot 13 is for the passage of the lugs 10 when 70 the plunger 9 is to be released from the tube 8. When the lugs 10 are at right angles to the slot 13, the tube 8 can be moved by the plunger rod 7 and by the plunger 9. The plug 12 has downwardly projecting lugs 14 75 rigid therewith. For filling the tube 8 with grease, the rod 7 will be turned and the lugs 10 will engage the lugs 14 and thus unscrew the tube 8 from the cap 2. The cap 2 can then be swung to the dotted outline position 80 of Fig. 1 and clamped in this position. The rod 7 by means of the lugs 10 is used to push the tube 8 to the position shown in Fig. 4 for filling purpose. The tube 8 is provided with an opening 15 to permit escape of air 85 during a filling operation. When the tube 8 goes back into the barrel 1, the perforation 15 will be closed by the wall of the barrel 1. When the tube 8 has been filled, it is drawn back within the barrel 1 by means of the 90 plunger 9. Thus the filler tube 8 is actuated by the plunger rod 7 with the plunger 9 and the lugs 10, and the tube 8 is released from the cap 2 by means of the plunger rod 7 and the lugs 14 on the 95 plug 12.

For discharging the grease, the plunger 9 can be released from the tube 8 by turning the plunger rod 7 until the lugs 10 will pass through the slot 13 and then pushing the 100 rod 7 inwardly. The rod 7 can then be actuated manually or by ratchet mechanism. Notches 16 are cut in the side of the rod 7. A handle 17 is pivotally mounted on a bracket 19 which is rigid with the barrel 1 105 and provided with a swinging gravity dog 18 which is adapted to engage the notches 16, the notches 16 constituting ratchet teeth, or a rack. The grease is forced out of a discharge spout 20.

When the tube 8 is to be filled with grease, it is pushed out of the barrel 1, as above described, and then immersed in the grease for taking in a charge. It is then drawn 5 back within the barrel by means of the plunger 9, as above described, and then screwed into the cap 2 for locking the cap and tube 8 together and for locking the cap 2 to the barrel 1. Various changes in the sizes, proportions, and construction of the several parts may be made without departing from 10 my invention.

What I claim, is,—

1. A grease gun comprising a barrel, a 15 telescopic filling and dispensing member mounted in said barrel, and a plunger detachably connected to said filling member for moving said telescopic filling member in and out of said barrel and for discharging grease from said filling member.
2. A grease gun comprising a barrel, a 20 telescopic filling and dispensing member mounted in said barrel, a cap hingedly connected to said barrel, and a plunger detachably connected to said filling member for operating the same and provided with means for attaching and detaching said filling member to and from said cap.
3. A grease gun comprising a barrel, a 25 telescopic filling and dispensing member mounted in said barrel provided with a perforated plug and lugs depending from the plug, a cap hingedly connected to said barrel, and a plunger detachably connected to said filling member for actuating the same and provided with lugs for engaging the lugs of said plug for attaching and detaching said filling member to and from said cap.
4. A grease gun comprising a barrel, a 30 filling and dispensing member mounted in

said barrel, a cap hingedly connected to said barrel, a barrel plug rigid with said barrel having an interior cavity and a perforation therethrough, a perforated plug rigid with 45 said filling member provided with depending lugs, and a plunger detachably connected to said filling member and provided with horizontal lugs adapted to engage said depending lugs for attaching and detaching said filling member to and from said cap. 50

5. A grease gun comprising a barrel, a cap hingedly connected to said barrel and means on said barrel for holding said cap in open position, a telescopic filling member mounted in said barrel, and a plunger detachably 55 connected to said filling member for moving the same in and out of said barrel and provided with means for attaching and detaching said filling member to and from said cap.

6. A grease gun provided with a cap 60 hingedly connected thereto and provided with a discharge nozzle, a telescopic filling member mounted in said barrel, a plunger detachably connected to said filling member for moving the same in and out of said 65 barrel and provided with means for detaching and attaching said filling member from and to said cap, and means for actuating said plunger to discharge grease through said nozzle when detached from said filling member.

7. A grease gun comprising a barrel, a 70 telescopic filling tube mounted in said barrel and provided with a perforation for escape of air, and a plunger detachably connected to said filling tube for moving the same in and out of said barrel.

In testimony whereof, I set my hand, this 23rd day of August, 1918.

CHARLES R. MILLER.
